I. Briggs, Jr.

Trip Hammer.

N° 7,965.

Patented Mar. 11, 1851.

UNITED STATES PATENT OFFICE.

LUTHER BRIGGS, JR., OF BRAINTREE, MASSACHUSETTS.

METHOD OF ADJUSTING THE STROKE OF TRIP-HAMMERS.

Specification of Letters Patent No. 7,965, dated March 11, 1851.

To all whom it may concern:

Be it known that I, LUTHER BRIGGS, Jr., of Braintree, in the county of Norfolk and State of Massachusetts, have invented certain 5 new and useful Improvements in Trip-Hammers; and I hereby declare that the following is a full and exact description.

The accompanying sheet of drawings represents my improvements, and forms a part 10 of these specifications.

Figure 1, is an isometrical perspective view of the machine. Fig. 2, is a geometrical transverse section of the knuckle joints, and a portion of the lifting leg, showing the 15 manner in which the lifting leg passes through the joint.

In the drawings, A, represents the hammer, B, the anvil, C, the helve, D, the lifting leg, E, the elevator consisting of the arm 20 F, and the claw G, and having a knuckle joint at H for grasping the lifting leg when acted on by the cams I, I, which revolve with the shaft K to which the power is applied.

25 L is the regulator which consists of an inclined plane working transversely of the machine, in two appropriate grooves in the vertical supports M, M, its office being to raise or depress the elevator at pleasure.

30 The operation of my improved trip hammer will readily be perceived to be as follows: The shaft K being propelled by any convenient kind of motive power, operates upon the lifting leg of the hammer, not directly as is commonly the case, but through the medium of the elevator E. The lifting leg D being grasped anywhere, along its length by the joints H of the elevator E, which in turn is governed by the regulator 35

40 L, under the direction of the operator, thus it will be seen that my improved trip hammer is entirely under the control of the hammerman; the combined action of the lifting leg D, the elevator E, and the regu-

lator L, enabling him, to strike at pleasure, 45 any sized blow, on any sized piece of iron.

It will readily be perceived that the form of the machine might be somewhat altered, without in any degree abandoning its peculiar principles and operations; as for instance, 50 the elevator might be placed over the helve, instead of beneath it, as in the drawings; and the regulator might be constructed in the form of a screw, eccentric, or any equivalent contrivance, for the simple inclined 55 plane exhibited by the drawings, for raising and depressing the elevator.

Having thus described my invention, some of its advantages I deem to be as follows: First, simplicity and cheapness of its construction, and second, its peculiar adaptability to water power, while at the same time, it seems to combine nearly all the capacities and facility of regulation of the 60 steam hammers.

65 What I claim as my invention, and desire to secure by Letters Patent, is—

The construction of a trip hammer, in which the hammer is raised by cams, not acting directly, upon the hammer or the helve, 70 or a projection, from the same, commonly called the lifting leg; but by the intervention of a movable joint so constructed, as to grasp, or clutch, the lifting leg at any required height, the position of the same, 75 being governed by the regulator, which may be constructed in the form of an inclined plane or any equivalent contrivance, for raising and depressing the joints at the will of the operator, the whole being constructed 80 to perform the peculiar services substantially in the manner hereinbefore set forth in this my specification.

LUTHER BRIGGS, JR.
